SOFA-BED HINGE

Edwin G. Krakauer, Brooklyn, N. Y., assignor to
 Kay Manufacturing Corporation, Brooklyn,
 N. Y., a corporation of New York

Application November 5, 1949, Serial No. 125,761

14 Claims. (Cl. 5—47)

1

This invention relates to the hinges for sofa-beds and particularly to the type which may be alternately locked in one position and released to move into another position during the conversion of the sofa-bed from a sofa into a bed and vice versa.

The present invention contemplates the provision of a simple but efficient sofa-bed hinge in which the locking and releasing means operates effectively in any position of the hinge in the sofa-bed and independently of the effect of gravity and which is not likely to become jammed or to fail to operate over long periods of time or after disuse for a considerable period.

The invention further contemplates the provision of a pair of cooperating overlapping releasing pawls carried by a spring-pressed locking lever and positively operated mechanically by the locking pin or bail on one of the hinge members to release the hinge for swinging movement of the hinge members relatively to each other by positively removing the locking pin from the locking lever by means of one pawl which initiates the releasing movement without the aid of gravity or of springs other than that pressing on the locking lever, the pin being carried clear of said one pawl by means of the other pawl which completes the releasing movement of the pin.

The invention further contemplates the provision of means for limiting the releasing movement of the pawls, which are suitably shaped to insure the positive and dependable release or unlocking of the hinge only when desired and the positive locking of the hinge members together when desired.

The various objects of the invention will be clear from the description which follows and from the drawings, in which

Fig. 1 is a side elevational view of the hinge in its normal locked position wherein the back and seat, shown in dash-dot lines, are in the sofa-forming positions.

Fig. 2 is a similar view of the hinge in its reversed but still locked intermediate position wherein the seat is up and the back is down.

Fig. 3 is a similar fragmentary elevational view and partial sectional view of the releasing pawls and locking pin showing the positions assumed thereby at the beginning of the releasing operation.

Fig. 4 is a similar view thereof showing the locking pin moved out of one pawl and about to be transferred into the notch of the other pawl.

Fig. 5 is a similar view thereof showing said other pawl rotated somewhat from the position

2

thereof shown in Fig. 4 to carry the locking pin clear of said one pawl thereby to pass the notch and to complete the release of the pin.

Fig. 6 is a side elevational view of the hinge folded from the position of Fig. 2 to the bed-forming position after the hinge has been unlocked as shown in Fig. 5 and the seat dropped into horizontal position.

Fig. 7 is a side elevational view similar to Figs. 3—5 of the pawls and locking pin showing the positions thereof relatively to the locking notches after the seat has been raised from the position of Fig. 6 toward that of Fig. 2 preparatory to locking the hinge and swinging the parts back to the sofa-forming position of Fig. 1.

Fig. 8 is a cross sectional view of the locking lever and the releasing pawls taken on the line 8—8 of Fig. 3.

In the practical embodiment of the invention shown by way of example and as is now well understood in the art to which the invention pertains, the seat 10 (Fig. 1) is secured to one member 11 of the hinge while the back 12 is secured to the other hinge member 13, the hinge members 11 and 13 being hinged together by the pivot 14. The usual control and back support bar 15 is pivoted at its upper end 16 to the member 13 and at its lower end 17 is pivoted and arranged adjacent to an end of the support member 18. The other control bar 19 is pivoted at its upper end to the pivot 14 and at its lower end is pivoted to the support 18 by the pivot 20, the support being suitably secured to the couch frame 21. In Fig. 1, the seat, back and frame are indicated by dash-dot lines, the arrows indicating the direction of movement of the adjacent parts to carry the parts into the next succeeding position.

It will be understood that a set of parts, each set consisting of a support 18, a suitable spring as 22 secured to the bar 19 and to the support 18, hinge members 11 and 13, and control bars 15 and 19, is arranged at each end of the sofa. It will further be understood that in moving the seat and back and the hinge parts secured thereto from the normal seat-forming position of Fig. 1 to the bed-forming position of Fig. 6, the hinge members 11 and 13 are first locked together to move as a unit to the intermediate position of Fig. 2 thereby to carry the back only into a horizontal position the seat being in a raised position; whereafter the hinge is unlocked and the hinge member 11 and its seat swung relatively to the member 13 and lowered into the bed-forming position of Fig. 6. It will also be understood that in changing from the bed-forming position

of Fig. 6 to the sofa-forming position of Fig. 1, the seat and member 11 are first raised into the intermediate position of Fig. 2 and locked, and the thus locked together hinge members and seat and back finally swung as a unit into the seat forming position.

With the above described usual operation of hinges of the present type in mind, the description of the novel release pawls 23 and 24 and of the channel shaped locking lever 25 may now proceed. The pawl 23 serves to initiate the release and the pawl 24 to complete the release of the hinge members as will later herein be fully explained. Said lever 25 is pivoted at one end 26 to the hinge member 13 and passes through the U-shaped bail 27 and swings between the legs 28 and 29 of the bail, which legs are secured to the hinge member 11. The leg 29 of the bail serves as the locking pin for the hinge when it enters the similar laterally aligned notches 30 and 31 in the respective parallel spaced side walls 32 and 33 of the locking lever (Fig. 8). Integrally connecting said side walls is the top wall 34 imparting a U-shape or channel cross section to the lever. Urging the lever to rotate about its pivot in a clockwise direction as viewed in Figs. 1 to 7 whenever the other parts permit the lever so to rotate, is the bent spring 35, one leg of which is anchored to the hinge member 13 as at 36 and the other to the locking lever as at 37 after the spring has been bent around the pivot 26.

The release pawls are pivotally mounted in overlapping relation in the space 38 between the side walls of the locking lever, one pawl as 23 being pivotally mounted on the pivot pin 39 near the free end of the locking lever and the other pawl 24 being mounted on the pivot pin 40 in longitudinal spaced relation to the pin 39, both pins passing through the side walls of the locking lever. The combined thicknesses of the pawls is less than the width of the space 38 so that the pawls may swing independently of and across each other into and out of the space and across the notches 39 and 31 of the locking lever. When swinging into the space 38, the pawl 23 rotates in a clockwise direction, and the pawl 24 swings in the opposite or counterclockwise direction to enter the space, therefore it may be said that the pawls are mounted for pivotal movement in opposite directions.

Means are provided to limit the swinging movement of the pawls in both directions. In the retracted positions of the pawls, wherein they are as far inside of the locking lever as they can go, the pivot pin 40 for the pawl 24 serves as a stop for the other pawl 23 by engaging the long concave inner edge thereof as best seen in Fig. 7. Similarly, the pin 39 serves as a stop to limit the retracting movement of the pawl 24 by engaging the long inner concave edge thereof as seen in Figs. 3, 4 and 7. The respective inner edges of the pawls themselves serve as stops to limit the extended positions of the pawls out of the lever, the end portion 41 of the inner edge of the pawl 23 engaging the inner surface of the top wall 34 of the lever as shown in Fig. 4 and the end portion 42 of the inner edge of the pawl 24 engaging said inner surface of the top wall 34 as shown in Fig. 5 to prevent the pawls from swinging too far. The inner edge of each of the pawls is preferably made generally concave to permit the pawl to be sufficiently retracted into the locking lever to be out of the way of the locking pin 29 when said pin is removed from the notches 30 and 31 to unlock the hinge.

The outer edges of the pawls are properly shaped to perform their releasing functions. That is, the edge 43 of the pawl 23 has the notch 44 therein, one edge 45 of which is longer than the opposite edge 46, to form the generally triangular projecting tongue 47 on one side of the notch. The edge 45 may be undercut or concavely arcuate and concentric with the pivot 39. The corresponding edges 48 of the notches 30 and 31 have the same curvature and register with the edge 45 in the locked position of the hinge shown in Figs. 1 and 2 and in the fully retracted position of the pawl 23 shown in Fig. 7. The pawl notch 44 is slightly wider than the diameter of the pin 29 and its edge 46 is forcibly engaged by said pin when the releasing operation is initiated (Fig. 3) while the edges of the notches 30 and 31 are then free of the pin. Said edge 46 is preferably straight and its arrangement is such that the pin 29 will not slide out along said edge when the hinge member 11 is raised in the direction of the arrow from the position shown in Fig. 1. The notches 30 and 31 in the locking lever are considerably wider than the pin 29 and the notch 44 to permit the pin to assume the position thereof shown in Fig. 7 just prior to locking, the pin being out of the notch 44 but in the notches 30 and 31.

The outer edge of the pawl 24 is preferably recessed as at 50 at about the middle thereof to allow the pin 29 to enter the locking notches 30 and 31 when the pawl is retracted and the pin has not yet entered the notch 44 as shown in Fig. 7. The pin 29 in its upward movement into the position of Fig. 7 is adapted to engage an edge of the recess 50 to move the pawl 24 out of the way and to permit the pin to lock the hinge members by dropping back into and entering the notches 44, 30 and 31 when the hinge member 11 is released, as will later be more fully explained. An end recess or notch 51 having two side edges 52 and 53, is made at the outer corner of the free end of the pawl 24 for the reception of the pin 29 as shown in Fig. 5 to carry the locking pin clear of the notches and around the pawl 23 thereby to complete the releasing or unlocking operation. The provision of the notch 51 results in the formation of the pawl tongue 54 between said notch and the recess 50.

Normally, the parts are in the locked positions of Fig. 1, the pin 29 being in the notch 44 of the pawl 23 and in the notches 30 and 31 of the locking lever 25. In this position, the weight of the back 12 presses the lever 25 downwardly against the pin 29 and maintains the pin in the notches against displacement, while the pawl 24 is inoperative but is held retracted inside the lever by the engagement of the pin with an edge part of the recess 50. The seat is lowered or horizontal and the back is up, so that the parts are in sofa-forming position. To convert to the bed-forming position, the parts are maintained locked and the seat and back are rotated as a unit as shown by the arrows of Fig. 1 into the intermediate position of Fig. 2, the back now being horizontal and the seat being raised as indicated by the positions of the hinge members 13 and 11 respectively. To lower the thus raised seat or hinge member 11 into the bed-forming position, the seat is first raised as far as it will go in the direction of the arrow from the position of Fig. 2 to swing the hinge member 11 counterclockwise about the hinge pivot 14. The consequent slight movement of the hinge-member 11 raises the pin 29 through a short arc

having the pivot 14 as a center, causing counterclockwise rotation of the locking lever against the action of the spring 35 about its pivot 26 to a greater extent than the rotation of the hinge member 11 whereby the lever moves relatively to and away from the pin. This is because the pin 29 tends to move in an arc approaching the pivot 39 of the pawl 23, but cannot move closer to the pivot because such movement is resisted by the pawl 23. Hence the pin is pressed forcibly against the notch edge 46 and then exerts a compressive force on the pawl 23 to cause the pivot 39 to move counterclockwise in an arc about the lever pivot 26 as a center, fulcruming as it does so about the relatively slightly moving pin 29, whereby said pin and the adjacent part of the pawl 23 against which it is pressed, is exposed, the locking lever withdrawing away from the pin, and the pawl 23 being thereby, in effect, rotated out of the notches of the locking lever to the position of Fig. 3 to initiate the releasing operation. Such movement of the pawl relatively to the lever carries the edge 46 of the notch 44 into a position in which it is tangent to the curved edge 55 of the tongue 54. When the pawl 24 is engaged by the pin just before said pin slides off the notch edge 46, said pawl is rotated against the stop pivot 39. It will be noted that in the position of Fig. 3, the end 41 of the pawl 23 is stopped by the wall 34 and cannot rotate in a counterclockwise direction. Hence, on further lifting movement of the hinge member 11, the pin slides out of the notch 44 and is transferred on to the curved edge 55 of the pawl 24 out of the notches 30 and 31, as shown in Fig. 4.

From the position of Fig. 4, continued lifting of the hinge member 11 carries the pin 29 against the lower edges of the side walls 32 and 33 of the locking lever beyond the notches 30 and 31 and into the corner recess 51 of the pawl 24 and causes the pin to rotate the lever against the action of the spring 35 until the lever is stopped by a suitable stop such as the leg 28 of the bail 27 which engages the top wall 34 of the lever. Further lifting of the hinge member 11 is thereby prevented. Since the seat cannot then be raised any further, any additional movement thereof to complete the releasing movement must be in a downward direction. Such lowering of the seat and its hinge member causes the pin 29 to seat firmly in the recess 51 against the edge 53 thereof and to rotate the pawl 24 about its pivot 40 toward and past the position thereof shown in Fig. 5 and until the end 42 thereof is stopped by the top wall 34 of the lever, said lever moving slightly clockwise under the influence of the spring 35 as far as is permitted by the pin 29 and the pawl 24. Further lowering of the seat and the pin 29 while the pawl 24 is stopped, causes the pin to slip off the edge 53 to complete the releasing movement of the pawl which has carried the pin around the other pawl 23 and away from the lever, thereby permitting the seat to be lowered into the position of Fig. 6. As soon as the pin 29 leaves the recess 51, the lever 25 is freed, since the pin has been swung by the pawl 24 to a position considerably below the lever. The thus freed lever is acted on by the spring 35 to swing the lower edges of the lever against the pin, which slides downwardly along said edges as the seat and hinge member 11 are lowered to the bed-forming position of Fig. 6. It will be understood that if the pawl 24 were omitted, it would become difficult to unlock the hinge, because upward movement of

the member 11 would result merely in carrying the pin out of the locking notches, and downward movement of said member would merely reinsert the pin into the notches.

5 It will be noted that the movement of the pawl 24 above described is accomplished positively and dependably under the direct force exerted on the pin and therethrough on the pawl by the movement of the hinge member 11. It will also be noted that should the tongue 47 of the pawl 23 be projected or positioned in the path of the pin while said pin moves with the pawl 24, then the rounded surface of the pin acts as a cam to move the tongue out of its way by swinging the pawl 23 in a clockwise direction enough to retract or to push said pawl back into the space 38 between the side walls of the lever. When it is desired to re-convert from a bed to a sofa, the operations just described are reversed, the seat being first raised from the position of Fig. 6 to the intermediate locked position of Fig. 2. As the seat and hinge member 11 are lifted out of the position of Fig. 6, the pin 29 slides along the lower edges of the lever, rotating said lever counterclockwise against the action of the spring 35 until the pin approaches the notches 30, 31. If the pawl 23 projects out of the lever, then the pin engages the tongue 47 and swings the pawl clockwise about its pivot to retract the pawl into the lever. Similarly, if the tongue 55 of the pawl 24 projects out of the lever, it is pushed back thereto, thereby to expose the locking notches 30, 31. As the pin passes the nearer corners of said notches, it frees the lever for the action of the spring 35, which swings said lever clockwise to carry the pin against the outer edge 43 of the completely retracted pawl 23 into the position shown in Fig. 7, in which the pin is also pressed against the further edges of the locking notches 30, 31 by the lifting force on the hinge member 11. The hinge parts are thereby temporarily locked and the member 11 cannot be lifted any further by the operator, who stops exerting lifting force thereon. Such release of the lifting force on the member causes it to drop slightly under the weight of the parts carried thereby, whereby the pin 29 drops into the lower parts of the notches 30 and 31 as well as into the notch 44 of the pawl 23 to lock the hinge members in the positions shown in Fig. 2 against relative movement, until the hinge member 11 is again deliberately lifted for releasing purposes. It will be noted that the pin cannot enter the notch 44 directly on the lifting of the hinge member 11 from the bed-forming position, but that the pin must first strike the remote edges of the locking notches in the lever and must then be dropped slightly to attain the final locking position. As the pin moves downwardly to pass the corner made by the intersection of the edges 43 and 43, the spring 35 again becomes effective to rotate the locking lever clockwise enough to cause the pin to enter all of the locking notches.

From the intermediate position of Fig. 2, the sofa-forming positions of the parts are reached by lowering the locked seat and hinged member 11, thereby raising the back and the member 13 in the usual manner. It will be understood that by the provision of separate pawls, I am enabled to attain positive action of the pawls for releasing and locking purposes without depending on springs or gravity to operate said pawls, and that the spring to operate the locking lever may be relatively heavy and strong to insure the desired action under all normal circumstances and con-

ditions even though the parts become rusty or tend to stick from disuse or the entry of dust or foreign matter into the device. It will further be understood that the hinge, while simple, is durable and efficient over long periods whether used frequently or not, and that the invention is well designed to accomplish its intended purposes.

While certain specific forms of the invention have herein been shown and described for illustrative purposes, it will be understood that various changes may obviously be made therein without departing from the spirit of the invention as defined in the appended claims.

I claim:

1. In a hinge of the character described provided with a pair of hinge members hinged together one of the hinge members carrying a spring-pressed locking lever having a locking notch therein, the other hinge member carrying a locking pin adapted to enter the notch to lock the hinge and to leave the notch to unlock the hinge on the manipulation of the hinge members, a pair of independently movable hinge-releasing overlapping pawls each having a pin-receiving notch therein and each pivoted to the lever, the pivot for one pawl being beyond one side edge of the locking notch and the pivot for the other pawl being arranged transversely of the other side edge of the locking notch, said one of the pawls being mounted to swing the notch thereof in an arcuate path about the pivot of said pawl and beyond the lever on the movement of said other hinge member in a given direction thereby removing the pin from the locking notch, transferring the pin to the notch of the other pawl on continued movement of said other hinge member in the given direction, and said other pawl being of sufficient length to extend beyond said one pawl and beyond the lever when said pawls are overlapped to the maximum extent, said other pawl on receiving the pin and on movement of said other hinge member in the opposite direction being adapted to carry the pin past said one pawl and past the locking notch.

2. The hinge of claim 1, the pawls being pivoted to the lever at respective points in longitudinal spaced relation to each other.

3. The hinge of claim 2, one edge of the pin-receiving notch of said one of the pawls registering with a corresponding edge of the locking notch of the lever when the hinge is locked and the pin is fully within the locking notch.

4. The hinge of claim 1, said other pawl having a tongue on one edge of the pin-receiving notch thereof and movable to position the tongue alternately into and out of juxtaposition to an edge of the pin-receiving notch of said one of the pawls to permit the transfer of said pin from said one of the pawls to the other pawl and then to permit movement of the pin with said other pawl as a unit and relatively to said one of the pawls.

5. In a hinge of the character described, a pair of hinge members pivoted together, locking means comprising a spring-pressed locking lever carried by one hinge member and having a locking notch in an edge thereof, and a locking pin carried by the other hinge member and arranged to enter the notch and to lock the hinge, and to leave the notch to unlock the hinge, and means to carry the pin out of the notch comprising a first pawl pivoted to the lever at a point beyond the locking notch and having an edge notch therein adjacent the locking notch and adapted to receive the pin, the notch of said pawl being spaced sufficiently from the pivot of the

5 pawl to swing with the pin as a unit out of the notch in the lever to a predetermined extent sufficient to initiate the unlocking of the hinge on the movement of the other hinge member in one direction, and a second pawl pivoted to the lever at a point in longitudinal spaced relation to the pivot point of the first pawl, said second pawl being arranged to move about the pivot point thereof independently of and across the first pawl and the lever, said second pawl having an edge recess therein in the path of the pin, a tongue on the outer end of the second pawl guarding the recess of the second pawl and extending at all times outwardly beyond the adjacent edge of the lever, the recess of the second pawl receiving the locking pin after said pin has been removed from the notch of the first pawl and moved outside of the lever past the tongue on the aforementioned movement of the other hinge member in said one direction, said second pawl swinging with the pin as a unit relatively to the first pawl and to the lever on movement of the other hinge member in the opposite direction and when the pin is received in the recess of the second pawl and held in said recess by the tongue thereby to carry the pin past the first pawl to complete the unlocking of the hinge.

6. The hinge of claim 5, the lever having a pair of spaced parallel walls and an integral wall connecting corresponding edges of the parallel walls, a pivot for each of the pawls passing through the parallel walls, and the pawls being arranged between the parallel walls in overlapping relation.

7. The hinge of claim 6, the pivot for the first pawl being in the path of the second pawl and the pivot for the second pawl being in the path of the first pawl, said pivots serving as stops to limit the movement of the pawls into the lever.

8. In a hinge of the character described provided with a pair of hinge members pivoted together, a spring-pressed locking lever carried by one of the members and having a locking notch therein adapted to receive a locking pin, a locking pin carried by the other member, means to remove the pin from the notch to release the hinge comprising a pair of overlapping and crossing pawls pivoted at such different points to the lever as to swing across the notch and across each other, each of the pawls having a pin-receiving edge notch therein, a tongue on each pawl forming a side of the notch in the corresponding pawl, each of the pawls being longer than the width of the lever thereby to carry the tongue of one pawl beyond the lever when said one pawl is swung in one direction and to carry the tongue of the other pawl beyond the lever when said other pawl is swung in the opposite direction, and means limiting the swinging movements of the pawls in both directions.

9. In a hinge of the character described, a first seat-carrying hinge member, a second back-carrying hinge member pivoted to the first hinge member, a U-shaped bail having two legs fixed to the first hinge member, a locking lever pivoted to the second hinge member and passing through the bail between the legs thereof, said lever having an edge notch therein for the reception of a leg of the bail whereby said leg serves as a locking pin to lock the members together against accidental relative movement, and means for removing the locking pin from the notch thereby to release the members comprising a first pawl having an edge notch therein adapted to receive the locking pin, said pawl being pivoted to the lever

to move in one direction away from and across the notch of the lever, and a second pawl pivoted to the lever at a point in longitudinal spaced relation to the pivot point of the first pawl to move in the opposite direction when moving away from the lever, the second pawl having a tongue on the outer edge thereof forming one side of a corner notch therein, said corner notch receiving the locking pin on predetermined initial releasing movement of the first hinge member in one direction and carrying the pin past the notch of the lever and around the free end of the first pawl on the final releasing movement of the first hinge member in the opposite direction.

10. The hinge of claim 9, a tongue on the first pawl adjacent the edge notch thereof, the tongues of said pawls being arranged in the path of movement of the pin for engagement by the pin in predetermined positions of the pawls to move the pin positively, and means limiting the movement of the pawls.

11. In a hinge of the character described, a pair of hinge members hinged together, a spring-pressed locking lever pivoted to one of the hinge members, a U-shaped bail having a pair of spaced legs secured to the other of the hinge members, one of said legs serving as a locking pin to lock the members together against relative movement, the lever being U-shaped in cross section and having a pair of laterally spaced apart side walls having laterally aligned locking notches in the respective corresponding edges thereof to receive said locking pin, said pin extending laterally of the lever, a first releasing pawl, a second releasing pawl, said pawls being arranged between the side walls of the lever to swing into and out of the lever, a pivot through the lever for the first pawl beyond the notches and adjacent the free end of the lever and in the path of the second pawl to limit the extent of retraction of the second pawl within the lever, said first pawl having an edge notch therein, one edge of said edge notch being arranged to register with the corresponding edges of the lever notches when said first pawl is retracted within the lever, a pivot for the second pawl passing through the side walls of the lever and in the path of, and serving as a stop for, said first pawl to limit the extent of the retraction of said first pawl within the lever, said first pawl being swingable in one direction out of the lever and the second pawl being swingable in the opposite direction and across the notches of the lever and out of the lever.

12. The hinge of claim 11, the respective ends of the pawls engaging the side edge portions of the lever to limit the extended positions of the pawls out of the lever, said pawls being freely swingable on the respective pivots thereof and being engaged by the locking pin and moved thereby on the movement of one hinge member relatively to the other hinge member out of the locking position to remove the pin from the locking notches.

13. In a hinge of the character described, a pair

of hinge members pivoted together for relative movement, means for locking said members against such movement comprising a locking pin projecting laterally from one hinge member and 5 a spring-pressed locking lever pivoted to the other hinge member and having a locking notch therein receiving the locking pin, and means for releasing the members for relative movement comprising a first pawl of greater length than the width 10 of the lever and pivoted to the lever and having a pin-receiving notch therein adapted to register with the locking notch and swingable away from the lever with the pin as a unit when the pin is in said pin-receiving notch on slight relative movement of the hinge members in a given direction to remove the pin from the notch of the lever, said pin leaving the notch of the pawl on continued relative movement of the hinge members 15 in the same direction to the limit of such movement thereby to initiate the unlocking of said hinge members, and a second pawl longer than the width of the lever and pivoted to the lever at a point in longitudinal spaced relation to the pivot point of the first pawl, the second pawl 20 having a pin-receiving recess therein in the path of the pin, and cooperating means on the lever and the pawls maintaining the pawls at all times in positions wherein the pawls cross each other, said means also limiting the pivotal movement of 25 the pawls relatively to each other in both clockwise and counterclockwise directions, the notch of the first pawl and the recess of the second pawl being each swingable into positions beyond an edge of the lever when the respective pawls are 30 engaged and moved by the pin.

14. In a hinge of the character described, a first hinge member, a second hinge member pivoted to the first hinge member, a locking pin fixed to the first hinge member, a locking lever pivoted to the 40 second hinge member and having an edge notch therein for the reception of the pin, a first pawl having an edge notch therein adapted to receive the locking pin, said pawl being pivoted to the lever at one point to move in one direction away 45 from and across the notch of the lever, a second pawl pivoted to the lever at a different point to move in the opposite direction when moving away from the lever, the second pawl having a pin-receiving notch therein, each of the pawls being longer than the width of the lever, and means maintaining the pawls in relatively crossed positions and for also limiting the movements of the 50 pawls.

EDWIN G. KRAKAUER.
